United States Patent

Des. 235,353
Patented June 10, 1975

235,353

CIGARETTE LIGHTER

George L. Schick, Trumbull, Conn., assignor to Warner-Lambert Company, Morris Plains, N.J.

Filed July 1, 1974, Ser. No. 484,642

Term of patent 14 years

Int. Cl. D27—05

U.S. Cl. D27—39

Fig. 1

Fig. 2

Fig. 3

FIG. 1 is a perspective view of a cigarette lighter showing my new design;

FIG. 2 is a rear elevational view thereof; and

FIG. 3 is a side elevational view thereof.

The side not shown is a mirror image of FIG. 3.

I claim:

The ornamental design for a cigarette lighter, as shown and described.
